UNITED STATES PATENT OFFICE.

JOHN KYLE, OF NEWARK, NEW JERSEY, ASSIGNOR TO THE CHALLENGE MACHINERY COMPANY, OF CHICAGO, ILLINOIS.

PRINTER'S BLOCK.

No. 823,416.

Specification of Letters Patent.

Patented June 12, 1906.

Application filed July 31, 1901. Serial No. 70,318.

To all whom it may concern:

Be it known that I, JOHN KYLE, a citizen of the United States, residing at Newark, in the county of Essex and State of New Jersey, have invented certain new and useful Improvements in Printers' Blocks, of which the following is a full, clear, and exact specification.

My invention relates to printers' blocks or hooks for holding stereotype and other printing plates; and it has for its primary object to provide a printer's block of such construction that the nut or turning head provided for the application of the wrench by which the movement of the hook relatively to the plate is effected may follow the hook back and forth, whereby much less space back of the hook for the manipulation of the turning head will be required and the screw may be rigidly fixed and therefore require much less material for its bearings at opposite ends thereof and as a consequence allow the hook to approach much closer than heretofore the edge of the block.

With these ends in view my invention consists in certain features of novelty in the construction, combination, and arrangement of parts by which the said objects and certain other objects hereinafter appearing are attained, all as fully described with reference to the accompanying drawings and more particularly pointed out in the claims.

In the said drawings, Figure 1 is a side elevation of my improved hook, showing the printing-plate in dotted lines. Fig. 2 is a plan view thereof, showing the hook at the limit of its retracted movement. Fig. 3 is a similar view showing the hook advanced. Fig. 4 is a vertical longitudinal section taken on the line 4 4, Fig. 2. Fig. 5 is a similar section taken on the line 5 5, Fig. 3. Fig. 6 is an end view. Fig. 7 is a cross-section taken on the line 7 7, Fig. 4; and Fig. 8 is a similar section taken on the line 8 8, Fig. 4.

1 represents the block proper, which may be composed of a solid block of metal or any other suitable material or constructed in any other manner so long as the upper side thereof be provided with a longitudinal slot 2, which extends from a point near one end of the block 1 entirely through the other end, and below this slot is formed a cylindrical cavity 3, also extending from a point near one end of the block entirely through the other

end, the cylindrical cavity 3 being of greater diameter than the width of the slot 2, as better shown in Fig. 7, so as to accommodate a round nut or turning head 4 and permit the latter to move back and forth along the cavity 3, but hold it against vertical movement through the slot 2. The nut or turning head 4 is provided in its outer face with radial wrench sockets or grooves 5 for the application of a pin or other suitable wrench which is passed downwardly through the slot 2 just back of the hook 6 in the usual manner, and said nut or turning head is threaded on a screw 7, which has its threaded extremity supported in a removable plate or disk 8 and its headed end 9 supported in a suitable counterbore in the opposite end of the block 1, as clearly shown in Figs. 4 and 5. The disk or plate 8 has threaded connection with the screw, so that by tightening the screw the disk will be drawn firmly against the end of block 1, which is recessed or mortised, as shown at 10, Figs. 4 and 5, for receiving the disk and holding it flush with the end of the block, and in order that the disk may not rotate with the screw the upper edge thereof is provided with a dovetail 11 projecting upwardly therefrom and being sheered off flush with the upper face of the block, as shown in Fig. 6, and seated in a corresponding dovetail mortise 12 in the end of the block, said dovetail mortise 12 being constituted by beveling the edges of slot 2 throughout a portion of their length, or so much thereof as is traversed by nut 4, as shown at 13, so that the bevel may perform the further useful purpose of allowing the wrench or turning key a greater range of movement in either direction. The screws 7 also constitute a guide and support for a slide 14, upon which is formed or secured a shank 15 of the hook; but this slide has no threaded connection with the screw and is held firmly against the nut 4 and caused to follow said nut during its receding movement by means of a coil-spring or other suitable cushion 16, sleeved on the screw 7 between the slide 14 and the inner end of the cavity 3. The hook and slide are caused to move in the opposite direction for gripping the plate by the nut 4, as will be understood. In order that the nut may not be deprived of any of its bearing upon the screw 7 and at the same time may be as thin as possible at its outer edge or periphery for per-

mitting the hook 6 to come as close to the end of the block as possible, the back of the hook and shank 15 are let into the inner face of the nut or turning head, or it might be described by stating that the inner end of the nut is let into the shank so as to underlie the hook, as shown at 17 in Figs. 4 and 5. By means of this construction it will be seen that inasmuch as the turning head follows the hook the space required back of the hook need at no time be greater than that which is necessary for the insertion of the wrench into the sockets in the turning head, and as a consequence a second plate may be placed much closer to the back of the hook than heretofore. It will also be seen that the screw 7, being stationary, it does not require extended bearings at its ends for its support, and as a consequence the disk or plate 8 by being composed of steel may be made comparatively thin, and therefore the entire distance between the end of the block—that is, the outer edge or face of disk 8 and the back of hook 6—need only be sufficient for the accommodation of the thickness of the disk and the sockets 5 in back of the turning head.

Having thus described my invention, what I claim as new therein, and desire to secure by Letters Patent, is—

1. In a printer's block, the combination of a block proper having a recess opened through the top and through one end, a disk closing the said end of the recess, a screw projecting longitudinally through said recess, and having one end bearing in the block proper, and the other end threaded in said disk, a hook projecting through the upper side of said recess, a slide sleeved loosely on said screw and supporting said hook, a spring sleeved on said screw between said slide and one end of the block proper, and a threaded turning head located on said screw between the other side of said slide and said disk, substantially as set forth.

2. In a printer's block, the combination of a block proper having a recess, a screw secured in said recess, a slide on said screw, a hook on said slide, a turning head threaded on said screw contiguous to said slide and hook, said turning head being let into the back of said slide and hook whereby the hook will overlie the turning head and a spring for pressing the turning head against the slide, substantially as set forth.

JOHN KYLE.
